CLAIM

The ornamental design for a mount for camera, smart phone or the like, as shown and described.

DESCRIPTION

FIG. 1 is a perspective view of a mount for camera, smart phone or the like showing my new design;

FIG. 2 is a front view thereof, the rear view being identical;

FIG. 3 is a left side view thereof, the opposite side view being identical;

FIG. 4 is a top view thereof; and,

FIG. 5 is a bottom view thereof.

The broken lines illustrate portions of the mount for camera, smart phone or the like which form no part of the claimed design.
